Richard Oliver.

ATTORNEY

UNITED STATES PATENT OFFICE.

JAMES S. GIBSON, OF CHICAGO, ILLINOIS.

WIRE-FENCE FASTENER.

1,264,384.

Specification of Letters Patent. Patented Apr. 30, 1918.

Application filed June 5, 1917. Serial No. 173,002.

To all whom it may concern:

Be it known that I, JAMES S. GIBSON, a citizen of the United States, residing at Chicago, in the county of Cook and State 5 of Illinois, have invented certain new and useful Improvements in Wire-Fence Fasteners, of which the following is a specification.

This invention relates to new and useful 10 improvements in fence posts and the principal object of the invention is to provide improved means for securing the wires to a cement post.

Another object of the invention is to provide 15 means for securing the wires in place without the use of staples and the like.

A further object of the invention is to provide means for detachably holding the 20 wire to the post so the wire may be removed therefrom whenever desired.

Another object of the invention is to provide 25 a device of this character, which is simple and durable in construction, reliable and efficient in operation and one which can be manufactured and placed upon the market at a minimum cost.

The invention also consists in certain other 30 features of construction and in the combination and arrangement of the several parts, to be hereinafter fully described, illustrated in the accompanying drawings and specifically pointed out in the appended claims.

In describing my invention in detail, reference 35 will be had to the accompanying drawings, wherein like characters denote like or corresponding parts throughout the several views, and in which:

Figure 1 is a front view of a portion of a 40 wire fence.

Fig. 2 is a section on line 2—2 of Fig. 1.

Fig. 3 is a front view of one of the wire 45 holding members.

Fig. 4 is a section on line 4—4 of Fig. 3.

In these figures 1 indicates the fence post, 50 preferably made of cement, while 2 indicates the wires of the fence. The holding means for these wires are indicated by the numeral 3, and each of these means comprises a casing 4 of rectangular shape, and 55 provided with a tubular extension 5, said extension curving outwardly where it joins the casing. 6 indicates the bore of the extension which communicates with the interior of the casing and a V shaped notch 7 is located in the top of the casing at each 60 side thereof, one of these notches being on

each side of the bore 6. 8 indicates the pin, preferably formed of one piece of metal, doubled upon itself to form the eyelet and then having the two parts of the metal 60 brought together and extended parallel to form the shank 9, this member being in the form of the well known cotter pin. This pin is adapted to have its shank passed through the bore 6, with only the eyelet extending 65 above the tubular extension. A filling piece 10 is inserted in the casing so as to entirely fill the same and this piece is provided with a V shaped projection 11 which engages the notches 7 and the center 70 part of this projection comes opposite the bore 6 so that when the pin 8 is driven in its split ends striking said projection will be forced apart and will curve up against the top of the casing as shown in Fig. 4. 75

After the parts of the wire holding members are assembled as in Fig. 4, they are embedded in the cement with the top of the tubular extension flush with the face of the post so that the eyelets project beyond the 80 said face. In putting the fence up the pins are placed over the strands thereof and the split ends pinched together and placed in the bore 6. The pin is then driven in and its ends upset as before described. When 85 desired the pins may be pulled out by a hammer or staple puller to release the fence.

It will be understood that due to the peculiar shape of the holding members they are rigidly held in the cement and that the 90 pins are securely held in the members by having their curved up ends locked in the casings by means of the filling pieces 10.

It is thought from the foregoing that the 95 advantages and novel features of my invention will be readily apparent.

I desire it to be understood that I may make slight changes in the construction and in the combination and arrangement of the several parts, provided that such changes 100 fall within the scope of the appended claims.

I claim as my invention:

1. A fence post including a plurality of cotter pins to engage the wires of the fence, 105 holding members in said post each having a bore to receive the arms of the cotter pin, said member having a V-shaped recess extending upon opposite sides of said bore, and a block in said member having a V- 110 shaped rib thereon adapted for engagement with said V-shaped recess and adapted to

bridge the bore through the holding member for spreading the ends of the cotter pin when the same is driven in the bore and engages said V-shaped rib.

- 5 2. A fence post comprising a series of members spaced apart and embedded in the post, each member comprising an enlarged casing having a tubular extension and having notches across the top of the same on
10 each side of the bore of the tubular extension, a filling piece for the casing having a projection thereon for engaging with the

notches and a member having an eyelet and with its shank extending through the bore of the extension and having its ends divided and bent over to engage the top of the casing on each side of the projection. ¹⁵

In testimony whereof I affix my signature in presence of two witnesses.

JAMES S. GIBSON.
